UNITED STATES PATENT OFFICE.

DAVID HARRISON SHERIFF, JR., OF KANSAS CITY, MISSOURI.

POTENTIOMETER.

Application filed March 5, 1923. Serial No. 622,936.

To all whom it may concern:

Be it known that I, DAVID HARRISON SHERIFF, Jr., a citizen of the United States, residing at Kansas City, in the county of Jackson and State of Missouri, have invented certain new and useful Improvements in Potentiometers, of which the following is a specification.

My invention relates to certain new and useful improvements in potentiometers and it primarily has for its objects to provide such an instrument by the use of which a plurality of circuits may be controlled from one unit, and to provide such an instrument in which the condensers for the several circuits are contained or embodied in the instrument itself, thus making a single unit of the condenser and potentiometer proper.

In its more specific nature the invention further resides in those novel details of construction, combination and arrangement of parts, all of which will be first fully explained, then be specifically pointed out in the appended claims, reference being had to the accompanying drawings in which:

Figure 1 is a rear elevation of one embodiment of the invention.

Figure 2 is a vertical cross section on the line 2—2 of Figure 1.

Figure 3 is a vertical section on the line 3—3 of Figure 2 showing one condenser arrangement.

Figure 4 is a diagrammatic view of the circuit arrangement of the unit and showing the outside circuit connections in dotted lines.

Figure 5 is a diagrammatic view of a modified form of the invention showing the resistance units in several sections with the contact fingers, one cooperating with each resistance unit.

In the drawings, in which like numerals and letters of reference designate like parts in all the figures, 1 represents the base which is preferably made of vulcanite, vulcanized fiber, bakelite or other suitable insulating composition. The base 1 is apertured at 2 to constitute a bearing for the adjusting sleeves and the base is also provided with a resistance unit 3. The unit 3 is preferably mounted on the back of the base and has circuit terminals connected to binding posts

4 and 5 with which the outside battery or source of E. M. F. 32 is adapted to be connected.

The adjusting sleeves or spindles comprise a central shaft 6 having a shoulder 7 and a finger piece 8 by which the spindle 6 may be turned. Mounted on the spindle 6 is a tubular spindle or sleeve 9 that turns loosely on the spindle 6 and is shouldered at 10 and is provided with a finger piece 11 by which it may be turned.

Mounted on the sleeve or hollow spindle 9 is another hollow spindle or sleeve 12 having a shoulder 13 and finger piece 14, the spindle 12 having a collar 15 by which the spindle 12 is held from endwise movement in the bearing 2. The spindle 12 is held against endwise movement in the bearing 2 by the shoulder 13 and an insulating collar 20 secured on the opposite end of the spindle 9, while the spindle 6 is similarly held by the shoulder 7 and insulating collar 16. Secured to the insulating collar 16 is a ring 17 carrying a springy contact finger 18 which engages the resistance element 3.

21 is a ring secured on the insulating collar 20 and carrying a springy contact finger 22 to engage the resistance element 3; while 25 designates a ring secured on the insulating ring 24 on the spindle 12 and carrying a springy contact finger 26 to engage the resistance element 3.

28, 29 and 30 indicate binding posts or contact terminals to which the rings 17, 21 and 25 are respectively connected by flexible wires 19, 23 and 27.

31 are stops for the fingers 18, 22 and 26 at the extremities of their adjustable positions.

Embedded within or associated with the base 1 are condenser sets A, B, C, D, E and F respectively, one plate of each of the condenser sets A, F and E being connected to the terminal 4; one plate of each of the condenser sets B, C and D is connected to the terminal 5. The other plate of each of the condenser sets A and B is electrically connected to the terminal 28, the other plate of each of the condenser sets C and F is connected with the terminal 29, while the other plate of each of the condenser sets D and C is connected with the terminal 30.

While the arrangement of the condenser

sets shown in Figure 3 is illustrated as one embodiment of my invention it is quite obvious that the arrangement may be altered to suit the desire of the designer, the principal feature being the association of the condenser with the potentiometer as a single unit to control one or more circuits.

In the practical use of the invention the frictional resistance of the springy contact fingers 18, 22 and 26 where they engage the coil 3 will be sufficient to prevent their turning unless their particular finger pieces 8, 11 or 14 are turned.

The embodiment of the invention shown in Figures 1 to 4 inclusive is illustrative of an arrangement by which three circuits may be controlled from one and the same insulating unit. It will, of course, be obvious that the number of circuit controls may be varied to suit the desires of the designers and within the limits of the practical size of the apparatus.

The external circuit connections have a common connection 33 with the posts 4 in which connection the battery 32 is contained while the other circuit lines 34, 35 and 36 connect respectively to the binding posts 28, 29 and 30.

From the foregoing it will be seen any one of the three circuits may be adjusted simply by turning its respective knob 8, 11 or 14, or all of the circuits may be adjusted by turning the respective finger piece or knob as desired.

Instead of making the resistance unit 3 as a single unit with all of the springy contact fingers engaging the same, it may be made of separate sub-units 3^a, 3^b and 3^c as indicated in Figure 5 and the springy contact fingers 18^a, 22^a and 26^a may be cor-

respondingly proportioned to engage the respective sub-units.

This potentiometer is primarily intended to be used as a tuning device of a radio device. The advantages of the device are greater economy in the material used, smaller panel space required and in some cases the reduced current consumption would be important.

From the foregoing description, taken in connection with the accompanying drawings, it is thought that the construction, operation and advantages of the invention will be clear to those skilled in the art.

What I claim is:

1. A potentiometer comprising a base, a resistance element mounted on the base, a plurality of contact fingers mounted on the base to turn on a common axis, said fingers lying in different planes with their contacting ends bent to lie in the same plane in engagement with said resistance element, those of the fingers overlying others having provision whereby they will pass over the fingers beneath, each of the contact fingers being adapted for variation over portions of the resistance element also covered by other of the contact fingers substantially as shown and described.

2. In a multiple potentiometer, a base, a resistance element associated with the base, a plurality of concentric spindles with operating knobs and contact fingers, the latter engaging said resistance element, terminal posts to which the ends of said resistance element are connected, and terminal posts to which said fingers are respectively connected.

DAVID HARRISON SHERIFF, JR.
